UNITED STATES PATENT OFFICE.

WILLIAM MILLARD, OF NEW YORK, N. Y., ASSIGNOR TO ALBALL MANUFACTURING COMPANY, OF BROOKLYN, NEW YORK, A CORPORATION OF NEW YORK.

DESIGN FOR A VENDING-MACHINE CASING.

42,175.

Specification for Design.

Patented Feb. 13, 1912.

Application filed August 23, 1911. Serial No. 645,656. Term of patent 14 years.

To all whom it may concern:

Be it known that I, WILLIAM MILLARD, a subject of Great Britain, residing at the borough of Manhattan, in the city, county, and State of New York, have invented a new, original, and ornamental Design for Vending-Machine Casings, of which the following is a specification, reference being had to the accompanying drawings, forming part thereof.

Figure 1 is an elevation of a vending ma-

chine casing, showing my new design; Fig. 2 is an elevation taken at 90 degrees from the elevation shown in Fig. 1; and Fig. 3 is a plan.

I claim:

The ornamental design for a vending machine casing as shown.

WILLIAM MILLARD.
